JAMES F. KUHN, OF EASTON, PENNSYLVANIA, ASSIGNOR OF ONE-HALF TO ALLEN C. FELLENCER, OF ALLENTOWN, PENNSYLVANIA.

SAFETY-FASTENING FOR JEWELRY.

1,259,877.

Specification of Letters Patent. Patented Mar. 19, 1918.

Application filed January 5, 1917. Serial No. 140,781.

To all whom it may concern:

Be it known that I, JAMES F. KUHN, a citizen of the United States, residing at Easton, in the county of Northampton and 5 State of Pennsylvania, have invented a new and useful Safety-Fastening for Jewelry, of which the following is a specification.

This invention relates to safety fastenings for brooches, or other similar articles of 10 jewelry.

The object is to provide a fastening means, to be applied to the back of a brooch, buckle, or similar article of jewelry, which, when properly adjusted, will prevent the 15 fastening pin from accidental dislodgement from the goods to which the same may be applied, and in which the several parts of the improved device are permanently secured to the brooch or other article, so that 20 it is impossible for them to become detached therefrom and lost.

Another object is to provide means for locking the fastening pin into engagement with the said goods, which may be readily 25 operated by the thumb and finger of the wearer, without the necessity of seeing the device, and which, when applied, is entirely hidden from view by the brooch or other article of jewelry.

30 A full and complete understanding of the invention may be obtained from a consideration of the following detailed description, taken in connection with the accompanying drawing forming part of this specification; 35 it being understood that while the drawing shows a practical form of the invention, the latter is not confined to strict conformity therewith, but may be changed or modified, so long as such changes or modifications 40 mark no material departure from the salient features of the invention, as specifically pointed out in the claims appended hereto.

In the drawing, in which like reference numerals designate corresponding parts in 45 each of the several figures:—

Figure 1 is a side elevation of the improved device shown attached to a brooch.

Fig. 2 is an elevation of the rear side thereof.

50 Fig. 3 is a longitudinal sectional view of the device showing the fastening pin in the open position.

Fig. 4 is an enlarged detail sectional view of the operating end of the pin.

55 Fig. 5 is a detail sectional view on the line 5—5 of Fig. 1.

While the device of the present invention is equally applicable to various forms and styles of brooches, buckles, pins, insignia, etc., it is deemed sufficient to illustrate the 60 improved fastening means as applied to a simple, conventional form of brooch in the drawing, wherein a body 1 is employed, which may be formed of any suitable metal and have any desired contour or design engraved or otherwise formed on the exposed face thereof. The body 1 has provided upon its rear side a pair of outstanding, spaced ears 2, preferably located adjacent to one end of the said body and secured thereto 70 in any desired manner. In the present instance, the ears are shown as composed of a single piece of metal having a connecting member 3, which is soldered or otherwise secured to the body. 75

Located adjacent the opposite end of the body 1 and in spaced relation to said ears 2, there is provided a tubular keeper 4 supported by a post 5, which is likewise soldered or otherwise secured to the said body 80 1. The keeper 4 has a tubular bore or passageway 6 formed entirely through the same, the axis of which extends longitudinally of the body member 1, and in alignment with the said ears, and is spaced away 85 from the rear or inner face of the body member 1, for a purpose to be described.

Mounted for pivotal movement between the ears 2 is a rockable sleeve 7 provided with an offset lug 8, which is adapted to fit 90 freely between the said ears 2, and to be loosely held therein by a pivot 9 passed through appropriate registering perforations formed in the lug 8 and the ears 2, said pivot, being properly upset at its ends 95 to retain it in place. The lug 8 is provided on the side adjacent to the post 5 with a shoulder 10, which is adapted, when the sleeve 7 is brought into parallelism with the body 1, to abut against the part 3 of the 100 ears 2, and form a stop to arrest further movement of the sleeve 7 in that direction. The remaining portion of the lug 8 is formed concentric with the axis of the pivot 9, and therefore permits the ready rocking 105 movement of the sleeve 7 in the opposite direction, as illustrated in Fig. 3.

A fastening pin 11 formed of any suitable metal is adapted to traverse the sleeve 7, and is of a length approximately equal 110 to the distance between the outer ends of the sleeve 7 and keeper 4, respectively. The

pin 11 is provided at one end with the usual penetrating point 12, and has secured on its other terminal an operating head 13, which is preferably, though not necessarily, milled 5 to facilitate the turning of said pin within the sleeve 7, for a purpose to be described.

A laterally disposed entrance opening 14 is provided on the inner end of the tubular keeper 4, and is formed by cutting away a 10 portion of the metal thereof located adjacent to the body member 1, as indicated in Fig. 5, said opening extending from the inner end of the tubular keeper 4 to the adjacent inner face of the post 5, which post, in the present

15 form is shown as being of less thickness than the length of the tubular keeper 4, the latter projecting from both sides of the post. This entrance opening 14 is for the purpose of permitting the point 12 of the fastening pin

20 11 to enter the bore of the tubular keeper 4, and to be afterward projected farther into the keeper 4 in a manner to be explained. The fastening pin 11 is threaded, as indicated at 15, adjacent to the head 13 for a 25 distance equal to the length of the rocking tubular sleeve 7, which in turn, is interiorly threaded at 16 for a distance equal to half its length and extending from the outer end thereof to its approximate center.

30 The outer diameter of the threads 15 is equal to the diameter of the fastening pin 11, and thus a shoulder 17 is in effect provided at the beginning of the threaded portion 15, which shoulder is adapted, when the 35 pin is unscrewed from the tubular sleeve 7, to come in contact with the threaded portion 16 of said sleeve 7 and to prevent the further unscrewing of the pin 11. On the other hand, the head 13 abuts against the adjacent 40 outer end of the tubular sleeve 7, and prevents further longitudinal movement of the pin 11 through the sleeve 7, when the said head is turned in the appropriate direction to screw the pin 11 into the sleeve 7.

45 In Fig. 3 of the drawing, the device is shown in a position to be applied to the apparel of a wearer, the shoulder 17 of the pin 11 abutting against the threads 16, and the said pin together with the sleeve 7 being 50 rocked upon the pivot 9 to remove the point of the pin away from the tubular keeper 4 for the purpose of passing the point through the goods to which the brooch is to be applied. The sleeve 7 and pin 11 are then 55 rocked upon the pivot 9 until the shoulder 10 bears against the member 3 of the ears and upon further pressure of the pin to cause a flexing of the same, as illustrated in dotted lines in Figs. 1 and 5, the point 12 of

60 the pin is brought around the end of the keeper to a position opposite the laterally disposed entrance opening 14, when the same may be sprung through the opening into alignment with the bore of the keeper 4.

65 When the pin 11 is in the position just de-

scribed, the point 12 is free to escape the adjacent face of the post 5, and to freely pass within said entrance opening 14. The shoulder 10 of the lug 8 bearing against the member 3 will cause an outward pressure of 70 the pointed end of the pin 11 against that wall of the keeper 4 remote from the entrance opening 14. This pressure, together with the pressure of the goods, contained between the fastening pin 11 and the body 75 member 1, will serve to prevent, at all times, the accidental displacement of the point 12 from the keeper 4, prior to the longitudinal movement of the pin 11.

After the brooch has been applied in the 80 manner described above, it is only necessary to turn the head 13 in a direction to screw the pin 11 through the tubular sleeve 7 until the head 13 abuts against the adjacent end of the sleeve 7, when the point 12 of the pin 85 is projected longitudinally beyond the end of the entrance opening 14, and thus it is impossible to remove the brooch from its applied position, until the reverse movement of the pin 11 has been effected. By reason 90 of the construction of the sleeve with the threads therein extending only a portion of the length thereof and the threads on the pin extending a distance equal to the length of the sleeve permits the adjustment of the pin 95 to engage in the keeper, and when so engaged, the threads of the pin are entirely concealed within the sleeve to avoid the possibility of the threads engaging with the fabric and thus damaging the same.

100 The device, when applied in position upon the clothes of a wearer, is entirely hidden from view by the body member 1 of the brooch, and it will be seen that the same may be readily removed therefrom by a simple 105 unscrewing action upon the head 13, and the proper manipulation to free the point 12 from the tubular keeper 4, through the entrance opening 14, and it will be further seen that all of the parts of the device are 110 permanently fixed to the brooch 1, so that there is no danger of separation.

From the foregoing, it will be seen that a simple, cheap, and durable fastening means for various articles of jewelry has 115 been devised, which may be manufactured at a low cost, and which effectually prevents the accidental displacement thereof from its applied position.

120 It will be understood that other mechanical means than the specific means shown for moving the pin longitudinally through the sleeve will be suggested to the mind of a skilled mechanic.

What is claimed is:—

125 1. In combination with a body member, a tubular keeper in spaced relation thereto, said keeper having a lateral entrance opening, a longitudinally disposed tubular sleeve threaded interiorly, means for pivoting said 130

sleeve to the body member in spaced relation to said keeper whereby said sleeve may be rocked, and a fastening pin having threaded engagement at one end with the pivoted 5 sleeve and an operating head at one end for turning the pin through the sleeve to cause the point thereof to enter through or to be withdrawn from the entrance opening of the keeper, the threads on the pin being entirely concealed within the sleeve when said 10 pin engages the keeper.

2. In combination with a body member, a tubular keeper in spaced relation thereto, said keeper having an entrance opening, a 15 longitudinally disposed tubular sleeve, which in its normal position is in alignment with the tubular keeper, means for pivoting said sleeve to the body member in spaced relation to said keeper, whereby said sleeve may be given a rocking movement, said sleeve being 20 threaded for a portion of its length, a fastening pin having one end threaded for a distance substantially equal to the length of the sleeve, and an operating head on the 25 pin beyond the threaded portion for turning the pin through the sleeve to cause the point thereof to enter through or be withdrawn from the entrance opening of the keeper, the terminals of the threads on the pin and 30 in the sleeve being coactive to limit the adjustment of the pin in one direction, while the head limits the reverse movement of said pin, the threads on the pin being en-

tirely concealed within the sleeve when said pin is engaged in the keeper. 35

3. Fastening means for an article of jewelry comprising a pair of spaced ears formed on the back of the article, a sleeve having a laterally offset lug directed toward the body of the article and mounted for pivotal 40 movement between said ears, said offset lug having a stop shoulder to limit the inward swinging of the sleeve, said sleeve being interiorly threaded approximately one-half 45 of the length of its bore, a fixed tubular keeper mounted upon the body in spaced relation to the sleeve and in longitudinal alignment therewith and having an entrance opening in the inner end, and a fastening pin mounted in the sleeve and having a manipulating head at one end and threaded, adjacent to said head for a distance substantially equal to the length of the sleeve, and pointed at the other end, said pointed end being adapted to be passed through the lateral entrance opening and then projected through the tubular keeper or withdrawn therefrom upon the proper turning of the said head. 50

55 In testimony, that I claim the foregoing as my own, I have hereto affixed my signature in the presence of two witnesses.

60 JAMES F. KUHN.
